(57) CLAIM

The ornamental design for a postpartum pad, as shown and described.

DESCRIPTION

FIG. 1 is a bottom perspective view of a postpartum pad, showing my new design;

FIG. 2 is a top perspective view thereof;

FIG. 3 is an end view thereof;

FIG. 4 is an end view thereof, opposite that shown in FIG. 3; and,

FIG. 5 is a top perspective view thereof, with the self sealing closure strip removed.
